COMBINATION DRILL POINT GAUGE, BEVEL PROTRACTOR, AND CENTER HEAD

Gladwin E. Johnson, Chicago, Ill.

Application April 13, 1936, Serial No. 74,027

3 Claims.

(Cl. 33—93)

This invention relates to a combination drill point gauge, bevel protractor and center head.

The main object of the invention is to produce a very simple tool comprising only two pieces 5 pivotally connected together, which provide a rigid gauge for measuring the angle and length of drill points, means for locating the centers of round objects, and means for defining and measuring angles.

10 The advantages of my invention will appear from the following specification.

In the drawing:

Fig. 1 is a plan view on an enlarged scale, of a combination tool embodying my invention, 15 showing in full and dotted lines two positions of the pivoted member.

Fig. 2 is a plan view of the device, also enlarged, with the pivoted member superimposed on the other.

20 Fig. 3 is a transverse sectional view taken in the plane of the line 3—3 of Fig. 2.

Fig. 4 is a side view of the tool as shown in Fig. 2.

The main member 10 comprises a flat piece of metal or other suitable material. Its elongated body portion has a straight edge 11 at one side, and a parallel, shorter straight edge 12 at the other, between which the body is provided with conventional linear measure markings. The 25 body of the member 10 is wider at one end than at the other, its straight edge 13 intersecting the edge 12 and extending at an angle of 121° to said edge 12. This angle was selected because conventional drill points are inclined at an angle of 59° to their axes, and therefore the correctness of a drill point may be gauged by placing one side of the drill body against the edge 12, with the point surface adjacent the edge 13, and comparing the drill point angle with the angle 30 of said edge 13. The drill point will be reground, if necessary, so that it will be parallel with said edge 13, when the axis of the drill is parallel with the edge 12, proving the drill point angle is correct.

45 It should be understood that the disposition of the edges 12 and 13 at an angle of 121° was selected for the preferred embodiment of the invention and its adaptation to a drill point gauge, but the invention is not limited in this respect 50 and other fixed angles suitable for comparison with devices other than drill points may be formed by the edges 12 and 13 without departing from my invention.

The edge 13 is provided with suitable markings for measuring the length of the drill point 55

or other object to be measured, and preferably the division lines of the markings extend parallel to the edge 12.

The member 10 is provided with a curved edge 14 between the edges 11 and 13, the center of the curve coinciding with the pivotal point 15. Protractor markings are provided, as shown, along the curved edge 14, and a line 16 marked "center head line" is provided for a purpose to be described.

10 The second member of the tool is indicated at 17 and it is pivotally connected to the member 10 by a countersunk rivet 18, the center of which is the pivotal point 15. The member 17 consists of an elongated portion having straight, 15 parallel edges 19, 20 and a head portion having converging edges 21, 22, forming a point 23. The particular form of the head portion and angular disposition of the edges 21, 22, may be varied, but in the present embodiment the protractor markings on the edge 14, the center head line 16, and the edge 22 of the pivoted member 17, are so arranged that when the pivoted member is moved to the dotted line position of Fig. 1 wherein the edge 22 coincides with the line 16, 25 the point 23 will be opposite 60½° on the protractor edge, and the edge 19 of the member 17 will then bisect the angle of 121° between the edges 12 and 13.

To use the tool as a protractor for drawing 30 angles on paper or the like, the pivoted member 17 is moved to a position wherein the point 23 registers with the desired angle marking, as for example 90°, as shown in full lines in Fig. 1. In that position, the edges 12 and 19 of the members 10 and 17, respectively, will be at a 90° angle to each other. When using the tool to measure angles, the pivoted member is moved until the edges 12 and 19 coincide with the lines defining the angle to be measured, and the point 23 will indicate the reading on the markings adjacent the edge 14.

To use the tool as a center head for locating the center of a round object, such as the circle 45 24, the member 10 is placed so that the edges 12 and 13 contact the circular wall or outline 24, and then the pivoted member 17 is moved to the dotted line position of Fig. 1, with the point 23 registering with 60½° and the edge 22 coinciding with the center head line 16. In this position the edge 19 of the member 17 bisects the angle defined by the edges 12 and 13. By drawing a line adjacent the edge 19 across the object 24, and repeating the procedure just de- 50 55

scribed after turning the object 24 about 90° , the center of the object will be located.

Of course, it will be understood that the edges 12 and 13 may be disposed at some angle other than 121° to each other and that this angle was selected for gauging drill points. Whatever the fixed angle may be, when the point 23 registers with the mark indicating one-half of that angle, the edge 19 will bisect the angle defined by the intersecting edges 12 and 13, and thus the center of a round object contacted by the edges 12 and 13 may be located.

To use the tool as a drill point gauge, the parts are preferably disposed as shown in Fig. 2, and the drill is placed against and parallel with the edge 12, the inclined surface of the point being parallel with the edge 13 or approximately so. If it is not truly parallel with said edge, the drill requires regrinding. The markings on the edge 13 are used to measure the length of the drill point.

Changes may be made in details of construction without departing from the scope of my invention and I do not intend to be limited to the exact form shown and described, except as set forth in the appended claims.

I claim:

1. A combination tool comprising an elongated flat body member having two straight intersecting edges forming a fixed obtuse angle at one side by the body between its ends, said angle being complementary to a drill point to be gauged, a protractor scale on the end of said body, and a second elongated member having a straight edged arm and an indicator head pivotally connected in superimposed relation to the said body, between the scale and said intersecting edges, one edge of said arm bisecting said fixed angle on the body member at its vortex when the indicator head registers with a point on the protractor scale designating a degree equal to one-half of said angle.

2. A combination tool comprising an elongated flat body member having two straight intersecting edges forming a fixed obtuse angle at one side of the body between its ends, said angle being complementary to a drill point to be gauged, 5 a protractor scale on the end of said body, and a second elongated member having a straight edged arm and an indicator head pivotally connected in superimposed relation to the said body, between the scale and said intersecting edges, a 10 center head line on the body member between the protractor scale and said pivotal connection, one edge of said arm bisecting said fixed angle on the body member at its vortex when one edge of the indicator head registers with the center head line on the body member and the indicator head registers with a point on the protractor scale designating a degree equal to one-half of said angle. 15

3. A combination tool comprising an elongated flat body member wider at one end than at the other and having two straight intersecting edges forming a fixed obtuse angle at one side of the body between its ends, said angle being complementary to an object to be gauged, the end edge 20 of the wider body portion being curved concentrically and provided with a protractor scale, and a second elongated member having a straight edged arm and a pointed indicator head pivotally 25 connected in superimposed relation to the said body axially of said protractor scale between the scale and said intersecting edges, and adapted to overlie the body member entirely within the margins of said body, one edge of said arm bisecting said fixed angle on the body member at its vortex when the indicator head registers with a point on the protractor scale designating a degree equal to one-half of said angle. 30
